UNITED STATES PATENT OFFICE.

JOHN J. LUTZ, OF LOUDON, TENNESSEE.

EXTENSION TABLE.

Application filed February 17, 1925. Serial No. 9,858.

This invention relates to extension tables comprising a main section and an auxiliary extension section adapted to be folded within the main section.

5 In the accompanying drawings,

Fig. 1 is a perspective view showing the table tilted to bring to view the bottom of the table, the auxiliary section being partially drawn out of the main section;

10 Fig. 2 is a longitudinal upright section;

Fig. 3 is an upright transverse section on the line, 3—3, of Fig. 2, looking toward the left;

15 Fig. 4 is a detail side elevation showing a corner of the table, parts being broken away;

Fig. 5 is a horizontal section at one of the corner legs in the main section of the table;

20 Fig. 6 is a similar section at one of the legs of the auxiliary section of the table.

Referring to said drawings, A is the top of the main section of the table. B, B are the side walls of said section. C is the end wall of the main section. The upper edges 25 of these walls bear against the lower face of said top and are suitably secured to said top. The ends of said walls meet the legs, D. A binding plate, D¹, is placed opposite each leg, D, and bears against the inner face of the adjacent side wall, B, and against the inner face of the adjacent end wall, C. A screw, D², extends horizontally through each such plate and into the adjacent leg, 30 D, and serves to draw said leg toward said plate, whereby the leg is drawn firmly against the adjacent ends of the walls, B and C. (See Figs. 1, 5 and 6.) To give the plates, D¹, good seating on the walls, B and C, the inner faces of said walls are provided 35 with notches, D³. These plates may also be secured to the adjacent walls by means of nails or screws, D⁴.

40 A bridge plate, E, extends transversely across the main section of the table and across the lower face of each side wall, B, B, at the ends of the latter, and is secured to said walls by means of screws, E¹. A leg, E², has its upper end bearing against the lower face of said bridge plate and is suitably secured thereto. The length of said leg is such 45 as to bring its lower end into the plane of the lower ends of the legs, D, D.

50 F is the top of the auxiliary section of the table. Its width is equal to the space between the inner faces of the side walls, B, B. F¹, F¹ are side walls extending downward

from the side edges of the top, F, the outer faces of said walls being even with the side edges of said top. An end wall, G, extends downward from the lower face of the top, F, 60 in position to let each end bear against one face of the adjacent auxiliary leg, H, the adjacent end of the adjacent side wall, F¹, bearing against one of the other faces of said leg. Adjacent each such leg, a binding plate, 65 D¹, is placed against the inner faces of the adjacent side walls and the adjacent end wall. Said binding plates are similar to and are secured the same as are the binding plates, D¹, already described as being applied to the 70 main section of the table. The legs, H, H, are of such length as will bring their lower ends into the plane of the lower ends of the legs, D, D, and E².

75 Between the inner ends of the side walls, F¹, is an inner end wall, G¹, even with the lower edges of those walls and reaching to the top, F.

80 On the outer face of each wall, F¹, of the auxiliary section of the table is a rib or tongue, F², extending horizontally from the adjacent leg, H, to the opposite end of said wall. Each of said tongues lies in a groove or channel, B¹, formed on the inner face of the adjacent side wall, B. Said tongues are 85 slidable endwise in said channels or grooves. This permits sliding the auxiliary table section endwise relative to the main table section.

90 The legs, H, H, are placed on the outer edges of the auxiliary top, F, in position to pass under the main top, A, and against the adjacent ends of the side walls, B, B, when the auxiliary section has been pushed 95 into the main section as far as it is intended to go. The drawings show the outer end edge of the auxiliary top, F, even with the corresponding edge of the top, A, when the auxiliary section has been thus folded. The drawings also show the auxiliary section 100 long enough to substantially reach to the binding blocks, D¹, of the main section when the auxiliary section has been thus folded.

105 To form a limit for the outward movement of the auxiliary section, a stop strip, I, is placed on the upper face of the bridge plate, E, in position to bear against the lower part of the auxiliary section end wall, G¹, when that section has been drawn out as far as it is to go. It will be observed that 110 when the auxiliary section has reached that position, the tongues, F², are still in the

grooves or channels, B¹, and the inner end of the auxiliary section is supported by said tongues and also by the bridge plate, E, the side walls, F¹, F¹, of the auxiliary section resting on the upper face of the bridge plate. When the auxiliary section has been thus extended, the leg, E², supports the bridge plate and the adjacent ends of the two table sections. Thus the entire extended structure is supported at each end by two corner legs and is supported intermediate its ends by the intermediate leg, E², extending downward from the bridge plate, E. When the structure is folded, the auxiliary section legs and the bridge plate leg, E², are near each other at the end of the structure. Excepting for the presence of the bridge plate leg and for the exposed outer end of the auxiliary top, F, the folded structure has the appearance of an ordinary table having a flat top and four corner legs.

It will be observed that the auxiliary section may be used when it has been moved out to its limit or only partially to its limit. For storage or shipment in knock-down form, the two corner legs, D, and the two corner legs, H, H, may be detached by releasing the screws, D², and placing the legs into the space between the side walls and end walls of the auxiliary section, and the bridge plate and the leg, E², may be moved by releasing the screws, E¹, by means of which the bridge plate is secured to the main section side walls, B, B.

I claim as my invention,

1. In an extension table, the combination of a main section having a fixed top and side walls and an auxiliary section extending into the main section and comprising a fixed top below the main section top and having side walls fitting to the inner face of the side walls of the main section, said sections having legs at their outer ends, the main section having a bridge plate at its inner end, the inner end of the auxiliary section and the bridge plate being formed and positioned for inter-engagement when the table is fully extended, and a leg attached to said bridge plate, substantially as described.

2. In an extension table, the combination of a main section having a fixed top and side walls and an auxiliary section extending into the main section and comprising a fixed top below the main section top and having side walls fitting to the inner face of the side walls of the main section and having an inner end wall, and said sections having legs at their outer ends, the main section having at its inner end a bridge plate bearing a stop, a leg fixed to said bridge plate, said stop abutting against said inner end wall when the table is fully extended, substantially as described.

In testimony whereof I have signed my name, this 16th day of February, in the year one thousand nine hundred and twenty-five.

JOHN J. LUTZ.
